CLAIM

The ornamental design for a ladder top cap, as shown and described.

DESCRIPTION

FIG. 1 is an upper perspective view of the ladder top cap showing my design.

FIG. 2 is a top plan view thereof;

FIG. 3 is a bottom plan view thereof;

FIG. 4 is a front elevation view thereof;

FIG. 5 is a back elevation view thereof;

FIG. 6 is a side view thereof; and,

FIG. 7 is an opposite side view thereof.

The ladder top cap is an attachment for a ladder.
